[57] CLAIM

The ornamental design for a drill stand, as shown.

DESCRIPTION

FIG. 1 is a front elevational view of a first embodiment of the drill stand showing our new design;

FIG. 2 is a right side elevational view thereof;

FIG. 3 is a left side elevational view thereof;

FIG. 4 is a rear side elevational view thereof;

FIG. 5 is a top plan view thereof;

FIG. 6 is a bottom plan view thereof;

FIG. 7 is a front elevational view of a second embodiment of the drill stand showing our new design;

FIG. 8 is a right side elevational view thereof;

FIG. 9 is a left side elevation view thereof;

FIG. 10 is a rear side elevational view thereof;

FIG. 11 is a top plan view thereof;

FIG. 12 is a bottom plan view thereof;

FIG. 13 is a front elevational view of a third embodiment of the drill stand showing our new design;

FIG. 14 is a right side elevational view thereof;

FIG. 15 is a left side elevational view thereof;

FIG. 16 is a rear side elevational view thereof;

FIG. 17 is a top plan view thereof; and,

FIG. 18 is a bottom plan view thereof;
